Edward Q. Norton.

UNITED STATES PATENT OFFICE.

EDWARD Q. NORTON, OF MOBILE, ALABAMA, ASSIGNOR TO THE ZADEK & NORTON PIANO-FORTE AND ORGAN COMPANY, OF ALABAMA.

UPRIGHT-PIANO-FORTE ACTION.

SPECIFICATION forming part of Letters Patent No. 375,327, dated December 20, 1887.

Application filed November 3, 1886. Serial No. 217,910. (No model.)

To all whom it may concern:

Be it known that I, EDWARD Q. NORTON, a citizen of the United States, residing in the port of Mobile, county of Mobile, and State of 5 Alabama, have invented a new and useful Improvement in Actions for Upright Piano-Fortes, of which the following is a specification.

My invention relates to an improvement in 10 the action of upright piano-fortes, in which a lifter, A, raises the whole action of the piano and disconnects it from the keys, at the same time substituting the pressure of a spring upon each key for that of the weight of the action; 15 and the objects of my improvements are to enable the keys to be used without making any sound, and also to relieve the action of all wear and consequent deterioration while the piano-forte is used for "five-finger" exercises 20 and other exercises requiring the repetition of a limited number of notes; also to enable more than one person to practice upon one piano-forte at the same time without producing interfering tones. I attain these objects by the 25 mechanism illustrated in the accompanying drawings, in which—

Figure 1 is a rear view of the lifter-frame. Fig. 2 is a front view of the same swung open. Fig. 3 is a vertical section of an upright-piano-forte action with lifter attached, showing mode 30 of operation of the lifter. Fig. 4 is a vertical section of the same piano-forte, showing the lifter as attached to the action of the piano-forte.

35 Similar letters refer to similar parts throughout the several views.

G G is a frame, made of wood or other suitable material, sufficiently strong to raise and support all the rockers and connected action 40 of an upright piano-forte.

I is the handle by which the lifter-frame G G is drawn out or pressed back into position.

A is a flange-rail, to which is screwed flange B, and in which rocker C works on pivot-pin 45 D when rocker C is raised by sticker E being lifted by key F.

In Fig. 3, G G is an end view of lifter-frame resting in stationary sockets H H, drawn forward by handle I, and the dotted lines indicate lifter-frame when pressed in so as to assume a perpendicular position. 50

J is one of a series of curved or spiral springs attached to the rear of the base of the lifter-frame, one to correspond with each key. Each spring is made with a resisting force equal to 55 that of the action of its corresponding hammer. Each spring is inserted into the base of the lifter-frame at such point and at such angle that when the lifter-frame is swung open and the action is in its normal position the 60 spring J is raised beyond the reach of the key F when the same is struck; but when the frame is pushed in and the action is disconnected from the key the spring is thrown forward and downward upon the key F, and resists any pressure upon the key with the same 65 force that is exercised by the action E when in its normal position.

The action of lifter-frame G G is as follows: When pressed in from the angular to the 70 straight or perpendicular position, the height of lifter-frame G G is increased and raises the whole action of the piano, including sticker E, by raising rockers C. Sticker E is disconnected from the key F, and the spring J, resting upon the key F, causes the key to respond to the touch of the fingers in playing; but there being no contact between sticker E and key F, all that part of the action above key F is not 75 operated. 80

I claim—

The combination, with a piano-action, of the oscillating lifter-frame composed of the hinged parts G G, supported in sockets H H, and the springs J, all constructed and arranged to 85 operate substantially as set forth.

E. Q. NORTON.
